UNITED STATES PATENT OFFICE

154,141

DESIGN FOR A FISHING SPINNER OR SIMILAR ARTICLE

Sven A. Pilblad, Boston, Mass.

Application March 6, 1947, Serial No. 137,389

Term of patent 7 years

(Cl. D31—4)

To all whom it may concern:

Be it known that I, Sven A. Pilblad, a citizen of the United States, residing at Boston, in the county of Suffolk, in the Commonwealth of Massachusetts, have invented a new, original and ornamental Design for a Fishing Spinner or Similar Article, of which the following is a specification, reference being had to the accompanying drawing, forming a part thereof, in which:

Figure 1 is a front elevational view, Figure 2 is a side edge elevational view, and Figure 3 is a sectional view taken on the line 3—3 of Figure 1, of a fishing spinner embodying my new design.

I claim:

The ornamental design for a fishing spinner or similar article, substantially as shown.

SVEN A. FILEBLAD.
